UNITED STATES PATENT OFFICE.

JAMES E. SMITH, OF EL PASO, TEXAS.

SAFETY DEVICE FOR STEAM-BOILERS.

No. 893,028.

Specification of Letters Patent.

Patented July 14, 1908.

Application filed August 16, 1907. Serial No. 388,839.

To all whom it may concern:

Be it known that I, JAMES E. SMITH, a citizen of the United States, residing at El Paso, in the county of El Paso and State of Texas, have invented a new and useful Safety Device for Steam-Boilers, of which the following is a specification.

This invention relates to safety devices for steam boilers, of that class, wherein when the water reaches a predetermined level, a fuse block is melted, whereupon the noise caused by the escaping steam will warn the engineer or fireman that the water is at a danger point in the boiler.

The object of the present invention is to provide an attachment of this character that shall be simple of construction, efficient and durable in use and in which the sounding of a false alarm will be positively prevented and the replacing of the melted fuse be rendered impossible without the knowledge of the chief engineer or master mechanic, so that a careless engineer may be readily detected. Furthermore, to provide an attachment combining the above characteristics and the added one of being adapted to operate before the water drops as low as the crown sheet, whereby to protect the latter from damage, and also to allow the engineer time to supply water to the boiler or to dump his fires.

With the above and other objects in view, as will appear as the nature of the invention is better understood, the same consists in the novel construction and combination of parts of a safety device for steam boilers as will be hereinafter fully described and claimed.

In the accompanying drawings forming a part of this specification and in which like characters of reference indicate corresponding parts,—Figure 1 is a view in vertical longitudinal section of a safety device constructed in accordance with the present invention. Fig. 2 is a horizontal sectional view taken on the line 2—2 of Fig. 1. Fig. 3 is a similar view taken on the line 3—3.

The device comprises a body or valve stem guide 1, the inner end of which is threaded into the boiler shell S over the crown sheet C and the outer end of which is reduced to provide a gland box 2 in which is housed an ordinary packing gland 3. The extension of the box 2 is threaded to receive a gland nut 4, which as usual, bears upon the gland and operates to force the latter into engagement with a packing (not shown) contained in a packing space 5. The body 1 is provided

with a threaded orifice that extends from a point adjacent to the space 5 to a point near its inner end, and engaging the orifice is a threaded intermediate portion 6 of the valve stem 7, the outer end of which carries a hand wheel 8 held in place by a lock nut 9. The inner end of the stem is provided with a head 10 that is arranged to fit within the combined valve and cup nut 11 that is interiorly threaded and engages the outer threaded end 12 of a fuse block valve stem 13. The connection between the valve stem 7 and valve stem 13 is of a swiveled character whereby to permit the former stem to turn without imparting motion to the latter. The outer face of the valve 11 is rounded, and fits into a similarly shaped seat 14 formed in the end of the body.

In order to hold the stem 13 from turning when the stem 7 is rotated, the former is provided with a polygonal head 15 that works in a similarly shaped bore 16 formed in a valve stem guide 17, the outer end of which has a threaded engagement with the inner end of the body. That portion of the guide 17 in which the inner end of the stem 13 works is circular in cross section and is of a diameter snugly to fit the stem. The inner end of the stem 13, which is made from a non-corrosive metal, is conoidal and constitutes a valve 18, the function of which will presently appear.

The fuse plug to which reference has been made comprises an inverted cup-shaped nipple 19 of iron or steel having a threaded connection with the crown sheet C of the boiler and is provided with a peripheral flange 20 formed with wrench faces, a thimble 21 threaded into the nipple and having wrench faces 22, and an inverted truncated cone-shaped fuse plug 23 of Banca tin, or of a fusible alloy.

It will be noted by reference to Fig. 1 that the outer end of the nipple projects some distance beyond the crown sheet, the object of this arrangement being to permit the fuse plug to blow out before the water is entirely off the crown sheet, thereby not only to protect the sheet from injury but also to afford the engineer or fireman time to supply water to the boiler or to dump his fires. The cup or dished portion of the nipple serves to prevent the flames from striking the fuse plug, thereby causing the latter to maintain a uniform temperature.

In order to prevent the renewal of the fuse plug without the knowledge of the chief en-

gineer, and to afford a ready means of detecting a careless fireman or engineer, a seal wire 24 is provided which is threaded through openings in lugs 25 and 26 carried respectively by the hand wheel and by the body 1, the ends of the wire being twisted together and secured by lead or other metallic seal 27. The die for the seal will be retained by the chief engineer so that if a plug is blown out 10 the person in authority will have ocular proof by the disrupting of the wire that a fuse block has been replaced and will be enabled to trace the person responsible for the accident.

15 Combined with the outer portion of the body is a whistle 28 that communicates with a passageway 29 which extends to the valve seat 14 and through which steam is supplied to sound the whistle. This steam is supplied 20 to the passageway through ports 30 and 31 in the inner walls of the guide 17 and through ports 32 arranged between the outer ends of the guide 17 and the inner end of the body.

25 The operation of the device is as follows: As soon as the water in the boiler lowers sufficiently to expose the upper end of the fuse plug the latter will melt and blow out and escaping steam will notify the engineer of the accident in time to supply water to the boiler 30 or to dump his fires. As soon as the accident occurs the hand wheel 8 is turned thereby breaking the wire and as the valve stem descends the valve 11 clears the passageway 29, whereupon the steam will rush through 35 the ports 30 31 and 32, thence through the passageway and cause the whistle to sound until the fuse plug is replaced, which, of course, can only be done after the furnace fires have become extinguished.

40 The valve 18 when seated in the thimble 21 will prevent the escape of steam and water from the boiler to the fire box until the plug has been replaced.

It will be seen from the foregoing description that although the improvements herein defined are simple in character they will be thoroughly efficient for the purpose designed and will in a positive manner secure the objects sought.

What is claimed is:—

1. The combination with a body, of a valve stem guide secured thereto and provided with ports, a fuse plug valve mounted within the guide and held against rotary movement relatively thereto, a valve stem 55 having a swivel connection with the fuse plug valve, and a combined valve and nut for connecting the fuse plug valve and the valve stem and operating, when the plug valve is seated, to permit the escape of steam for the purpose of sounding an alarm.

2. The combination with a body provided with a passageway, and a whistle communicating with one end of the passageway, of a valve stem guide secured to the body and 65 provided with ports normally out of communication with the passageway, a fuse plug valve mounted within the guide and held against rotary movement relatively thereto, a valve stem, a combined valve and nut connecting the valve stem and the fuse plug valve and arranged to permit the stem to have rotary movements independently of the fuse plug valve, the combined valve and nut operating normally to close the passageway 75 leading to the whistle, and a fuse plug arranged in the path of movement of the fuse plug valve.

In testimony that I claim the foregoing as my own, I have hereto affixed my signature 80 in the presence of two witnesses.

JAS. E. SMITH.
